UNITED STATES PATENT OFFICE

142,963

DESIGN FOR AN EARRING

Frank Morrow, Johnston, R. I.

Application July 11, 1945, Serial No. 120,624

Term of patent 3½ years

(Cl. D45—9)

To all whom it may concern:

Be it known that I, Frank Morrow, a citizen of the United States, residing at Johnston, in the county of Providence and State of Rhode Island, have invented a new, original, and ornamental Design for Earrings, of which the following is a specification, reference being had to the accompanying drawing, constituting a part thereof.

Fig. 1 is a front elevational view of an earring showing my new design; and

Fig. 2 is a side view thereof.

I claim:

The ornamental design for an earring, substantially as shown.

FRANK MORROW.
